V. S. Wedder, of Troy, New York.
user to

P. J. Myers, of Cleveland, Ohio.

Letters Patent No 1887 Dated Jan'y 5th 1867.

Design for a Cooks Stove.

The schedule referred to in these Letters Patent and making part of the same.

To all whom it may concern:

Be it known that I, V. S. Wedder, of the City of Troy,
in the County of Rensselaer, and State of New York, have invented or pro-
duced a certain new and original ornamental Design for a Cooking
Stove; and I do hereby declare that the following is a full and exact
description thereof, reference being had to the annexed photographs,
in which, Fig. 1. is a front view, and Fig. 2. a side view of a cooking stove
having my said ornamental design.

This ornamental design for a cooking stove consists of
the compound ornaments A. A. A. A. arranged upon plain panels
B. B. B. B. furnished with bead-like border mouldings C. C. C. C. and
transversely curved center mouldings D. D. D. D. so as to present the ap-
pearance represented by the annexed photographs.

What I claim as new and of my invention or production,
and desire to secure by Letters Patent, is the above described ornamental
design for a cooking stove.
